UNITED STATES PATENT OFFICE

2,327,072

VIOLIN PIANO

Erick Silen, Kelso, Wash.

Application September 28, 1942, Serial No. 459,999

3 Claims. (Cl. 84—256)

This invention relates to violin pianos and it is designed more especially as an improvement upon the structure disclosed in Patent 1,555,762, issued to me on September 29, 1925.

In the patented structure there is disclosed a bowing element in the form of a disk which, when brought into operative relation with a string, wipes on the string and thereby sets up vibration. It has been found in practice, however, that bowing disks disposed as disclosed in the patent, do not properly vibrate the strings because, when a disk is applied to a string, it not only wipes across the string but also wipes downwardly therealong with the result that the vibrations are deadened and the tone produced is not as brilliant as desired.

An object of the present invention is to so locate the bowing disks that they will exert a wiping action transversely of the wire or string and the downward wiping along the string, present in the patented structure, is substantially eliminated.

A still further object is to provide the bowing mechanism in a unit which is easily placed in or removed from the instrument in its entirety.

Another object is to simplify the mechanism utilized for operating the mechanism by eliminating the electric motor heretofore found necessary, the operating mechanism being of new and novel construction and being propelled by foot power.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a front elevation of a violin piano containing the present improvements, a portion being broken away to disclose some of the interior mechanism.

Figure 2 is a vertical section through the instrument taken from front to rear.

Figure 3 is an enlarged section taken vertically from front to rear through the bowing unit.

Figure 4 is a top plan view of the bowing unit, parts being broken away and its supporting structure being shown in section.

Figure 5 is an enlarged face view of one of the

bowing disks and illustrating its operative relation to one of the strings or wires of the instrument.

Figure 6 is a section on line 6—6, Fig. 5.

Figure 7 is a section on line 7—7, Fig. 4.

Figure 8 is a view partly in section and partly in front elevation of one end portion of the bowing unit, remote parts being removed.

Figure 9 is an enlarged side elevation of a portion of the driving mechanism, parts being shown in section and the positions of some of the parts being indicated by broken lines.

Figure 10 is a vertical section through a portion of the driving mechanism taken substantially on the line 10—10, Fig. 9.

Referring to the figures by characters of reference, A designates the cabinet portion of the instrument the keyboard of which has been indicated at B. C designates the strings located in the same manner as usual in a piano while the sounding board has been disclosed at D. The arrangement of the strings can be the same as that disclosed in my patent heretofore referred to and these strings can be sounded by hammers under the control of a pneumatic piano-playing mechanism. The mechanism includes the wind chest I, the pneumatics J and the tractor K. This piano-playing mechanism is of the usual type and constitutes no part of the present invention. Accordingly it has not been shown or described in detail.

The base 1 of the sounding board is extended back into the cabinet A and has side members or supports 2 extended upwardly from its side portions, these members being suitably braced at their upper ends by connecting brackets 3 attached to a frame 4.

A recess 5 is extended downwardly into the upper end of each strip or support 2 and provides seats to which are secured the ends of a cross-strip 6. A notch 7 is formed in one wall of each recess 5 and removably mounted on this cross-strip and extended into the two recesses, is the base 8 of the bowing unit. This base carries at its ends turnbuttons 9 adapted to be moved into the notches 7 for the purpose of locking the base in position and it is preferred to provide each of the turnbuttons with an eye or loop 10 whereby they can be grasped readily for the purpose of lifting the base 8 and the parts carried thereby out of position within the instrument.

An elongated housing 12 is secured on the base 8 and extends longitudinally thereof and located within this housing is a series of springs 13 which engage the offset portions 14 of shafts 18

which extend entirely through the housing and are suitably journalled therein, these shafts being covered and having their offset portions concealed by a housing cover 19. The forward end of each shaft has a crank 20 while the rear end of each shaft has an upwardly extended finger 21 carrying a roller 22. The downward pressure exerted on the offset portions 14 by the springs 13 serves to hold these fingers normally extended upwardly at points close to but in front of the vertical plane occupied by the strings C.

The forward ends or cranks 20 carry antifriction rollers 23 which bear downwardly on the heads 24 of screws 25 which, as shown, are adjustably mounted within rods 26 each of which is adapted to be actuated by one of the keys of the keyboard through a lifting rod 27 and a lever 28.

Bearing brackets 29 are extended backwardly from the upper portions of the side members or supports 2 and journalled in each of these is a short shaft 30. The two shafts are alined and have screw-threads 31 on those ends which are extended toward each other. The outer end of one of the shafts has a sprocket 32 which is adapted to receive motion through an endless chain 33 from a sprocket 34 journalled on a shaft 35 which is supported within the front portion of the cabinet A at the bottom thereof. A hub 36 is extended laterally from the sprocket 35 and has a circumferential V-shaped groove 37.

Interposed between the alined shafts 30 is a screw-threaded shaft 38 the ends of which are detachably connected to the shaft 30 by coupling sleeves 39 locked against relative rotation by nuts 40 on the shafts 30 and 38.

Shaft 38 is supported in front of but close to the strings C as clearly shown in Fig. 3 and adjustably secured to but rotatable with this shaft at points close to but at one side of each of the strings C is a bowing disk 41 each of which is formed of layers of flexible material cupped as shown, the said layers being secured to the shaft and bound together at their centers by nuts 42. Washers 43 are interposed between these nuts and the opposed faces of the bowing disks so that when the nuts are tightened the disks will not tend to buckle out of shape.

The upper marginal portion of each disk 41 is interposed between but out of contact with one of the strings C and one of the rollers 22. Thus when the bowing disk is rotating at a high speed due to the actuation of shafts 30 and 38 by chain 33, they will not normally contact with the adjacent strings. However when one of the shafts 18 is rotated against the action of its spring 13 by an upthrust from rod 26, the roller 22 and its finger 21 will be swung laterally against the upper marginal portion of the disk 41, thereby causing said upper marginal portion to flex laterally toward and to wipe across the adjacent string C. Consequently this string will be vibrated and sounded. At this point attention is directed to the important fact that in the present structure the string C is extended close to the axis of rotation of the disk 41 so that a downward wiping action on the string is reduced to the minimum and, consequently, a more brilliant tone is obtained than should the string be vibrated by a downward wiping action of the disk when the parts are located as in the patent heretofore referred to. In other words practically a straight-across movement of the disk on the string is set up in the present structure and, as a result, a brilliant, live tone is produced which has not

been possible heretofore. It is obvious of course that the lower portion of the disk does not contact with the string because it is not flexed. Only the upper backwardly moving portion of the disk engages the string.

It will be noted that all of the shafts 18 are carried by the housing 12 which, in turn is secured on the base 8. Thus by turning the wing nuts 9 so that they are moved out of the notches 7, base 8, housing 12, shafts 18 and other parts supported by the housing can be lifted out of the piano case so that parts can be reached readily for repairs or replacements. Furthermore, by unscrewing the sleeves 39 from the ends of the shaft 38, said shaft can be easily lifted bodily out of the instrument for repairs and replacements. This is an important item because heretofore it has been extremely difficult to make any adjustments or repairs due to the fact that it has not been possible readily to remove the mechanism requiring the adjustments, etc.

It will be noted by referring to Fig. 3 that the bowing disks are provided with the same rosin-applying means as shown in the patent mentioned, this including disks 44 carried by a hinged strip 45 and containing rings or the like of rosin which will be applied to the operative edges of the bowing disk whenever the hinged strip 45 is swung downwardly into the position shown in Fig. 3.

Heretofore it has been the practice to operate the bowing mechanism from an electric motor. It has been found more expedient to utilize foot power for this purpose and, with that end in view, there is provided a pulley 46 on the shaft 35. This pulley has a circumferential groove 47 which is V-shaped and it also has an extended hub 48 in which is formed a circumferential V-shaped groove 49. Both pulley 46 and pulley 34 have flat inner faces which contact with each other as shown in Fig. 10 and the shaft 35 on which the two pulleys are mounted is keyed to and rotates with the pulley 46 as indicated at 50.

A tubular shaft 51 is journalled at the bottom of the case A and is provided at one end with a crank 52 and at its other end with a crank 53. An arm 54 is supported by and is adapted to swing on one end portion of shaft 35 and is connected by a link 55 to the crank 53. The pin 56 connecting these parts 54 and 55 also engages an arcuate shoe 57 shaped to fit within the groove 49 as shown. The point of connection between this shoe and the pin 56 is well above the periphery of the hub 48 and toward the rear end of the shoe. Consequently when arm 54 is swung in a counterclockwise direction in Fig. 9, the advancing end of the shoe will tend to grip the walls of groove 49 and thus cause the hub 48 and pulley 46 to rotate. However, when the arm 54 is swung in the opposite direction the shoe is caused to ride out of gripping position so that it can turn in a clockwise direction while the hub 48 is still rotating in a counterclockwise direction.

An air pump in the form of a large bellows L forms a part of the pneumatic mechanism heretofore mentioned and is located where it will direct air into the chest I. This bellows has its movable side connected by a link 58 to the lower end of a hanger 59 supported by the fixed side of the bellows. The point of connection between these parts 58 and 59 also serves as a pivotal connection for one end of a link 60 which extends to and is pivotally joined to the lever 52 extending from tubular shaft 51. It also serves to join

another link 61 to the parts 59, and 60 and this link 61 is extended to and pivotally mounted on the inner end of a foot-pedal 62.

From the foregoing it will be noted that when the pedal 62 is thrust downwardly, the thrust will be transmitted through link 61 to the hanger-supported link 60 which, in turn, will transmit thrust through link 60 to arm 52. Consequently shaft 51 will be rotated in a counter-clockwise direction in Fig. 9 and cause crank arm 53 to actuate shoe 57 for the purpose of rotating hub 48 in a counterclockwise direction. In Fig. 10 these parts have been shown in one extreme position. When pressure is removed from pedal 62, said pedal will rise to its normal position through the action of the expanding bellows or through the lifting action exerted by spring 63 upon the pedal 62.

A shaft 64 is extended through and journaled within the shaft 51 and one end thereof is provided with a crank arm 65 connected by a link 66 to an arm 67 mounted to swing upon shaft 35. The pivot pin 68 connecting these parts also serves to carry an arcuate shoe 69 similar to the shoe 57 and adapted to fit within the angular groove 37. The operation of this shoe is similar to that described in connection with shoe 57, it being understood that when the shoe 69 is thrust in a counterclockwise direction it rotates hub 36 and pulley 34 whereas when it is moved in a clockwise direction, it automatically disengages itself from the walls of groove 37 so as to become recessed preparatory to repetition of its thrusting action.

A second bellows L' similar to the bellows L is connected to shaft 64 in the same manner as shaft 51 is connected to bellows L, some of the corresponding parts being indicated at 52', 58', 59' and 60'.

Obviously by alternately depressing the treading 62 and 62', the two shafts 51 and 64 can be alternately rotated in one direction, thereby to impart a continuous rotation in one direction to either or both the sprocket 34 and pulley 46. Rotation of the sprocket operates the bowing disk whereas rotation of pulley 46 drives the belt 70 which, in turn, propels the tremolo mechanism, 107-108 of my patent.

The weight of the pulleys is such that they act as fly-wheels so that a steady rotation can be maintained.

5 Damper-operating mechanism has been indicated generally at 71 and is to be controlled by hand. The damper has been indicated at 73. As the damper and its controls constitute no part of the present invention they have not been shown or described in detail.

6 Pulleys 34 and 46 can be bolted together as shown or can be made in one piece.

To insure a sweet musical tone in the violin 10 portion of the instrument it is necessary of course to use violin size strings.

What is claimed is:

1. In a violin piano, a sounding board, strings supported adjacent thereto, spaced alined shafts, 15 means for rotating one of the shafts, an interposed shaft detachably connected to and rotatable with the alined shafts, means for detachably connecting the interposed shaft to the alined shafts, a bowing disk adjacent to each of the 20 strings, all of the disks being adjustably mounted on the interposed shaft, and means for separately flexing the respective disks for contact with the adjacent strings.

2. In a violin piano a plurality of strings, 25 spaced alined shafts, means for rotating one of the shafts, an interposed shaft detachably connected at its ends to the alined shafts for rotation therewith, bowing disks adjustably mounted on the interposed shaft and rotatable 30 therewith, each of said disks being positioned close to but out of contact with one of the strings, all of the strings being located in a plane extending close to the axes of rotation of the disks and all of the disks being positioned to exert a backward wiping action only when applied to their adjacent strings, and means for flexing the respective disks while rotating to contact them with the adjacent strings.

3. In a violin piano the combination with 40 strings and a series of rotatable bowing disks of flexible material, of a supporting structure having seats, a cross-strip detachably and removably mounted at its ends on the seats, means for securing said cross-strip to the seats, said means 45 including turn-buttons, there being recesses in the supporting structure to receive the buttons, and separate means supported by the cross-strip and removable therewith as a unit for flexing the respective bowing disks.

ERICK SILEN.
